UNITED STATES PATENT OFFICE

KARR PARKER, OF BUFFALO, NEW YORK

SYSTEM OF RECEPTION AND REPRODUCTION OF RADIO PROGRAMS

Application filed September 13, 1927. Serial No. 219,242.

This invention relates to a system of reception and distribution of radio or telephonically received programs and to certain of the instrumentalities employed therein.

This invention is more particularly applicable to the distribution of entertainment features or programs to the various rooms of a hotel, and its principal object is a system, economical to install and maintain, by which the occupant of any room is enabled to diversify the features to which he listens by selecting at will and whenever desired either of at least two programs or entertainments which are being simultaneously distributed. The programs or entertainments which are offered for selection are primarily those which originate in radio broadcasting studios, but may include one or more programs otherwise originating such as a public address in the hotel in which the distribution of entertainment features is being made.

With the foregoing objects in view the invention consists generally in at least two incoming channels of communication to each room to be served, the number of such rooms being as many as desired, a sound reproducer for each of such rooms having connected therewith a selector switch mechanism operable at the will of the occupant and by which the reproducer may be coupled to either channel of communication, radio receivers, one for each channel of communication, and preferably a public address system having a line of communication which may be connected at will to any one of the aforesaid channels of communication. Thus, the occupant of a room may select any of the programs which come into his room to diversify his entertainment, and may also, in the case of an important speech or other important program originating within the building, select the same instead of a radio program if he so desires, and such diversity of entertainment is afforded while avoiding the vast expense

and complication of a radio receiver local to each room as has heretofore been proposed.

A further object is to provide a central station or control room for the accommodation and centralization of all operating equipment such as receiving and amplifying apparatus, switchboards and other accessories whereby all such equipment may be placed under the immediate supervision of a skilled operator who can maintain the system in operation and select the various programs which are to be offered to the occupants.

The invention also consists in various other features of construction and arrangement which will be pointed out as the description proceeds.

The number of programs to be offered is limited by economic and space considerations only, but in order to simplify the illustration of the invention, a system having a range of two simultaneous programs is shown, in which:

Figure 1 is a schematic diagram of the control room equipment and incoming circuit connections.

Figure 2 is a schematic diagram of head set and loud speaker communication channels connecting the various rooms to the control room.

Figure 3 is a schematic diagram of the guest room, selector switch and circuit connections.

Figure 4 is a perspective view of the somno.

Figure 5 is a perspective view of the somno drawer (partly broken), showing the selector switchbox and head set.

Figure 6 is a perspective view of a loud speaker coordinated to the present system.

The specific equipment utilized in the control room is of any suitable type and hence no detailed explanation thereof will be given. The outside or radio programs are received amplified and rectified by radio receiving sets 1 and 2 and the resulting sound currents conducted by the conductors 3 and 4 to the

switches 5 and 6 on the switchboard 7, said switches providing the means by which the radio sets may be connected to their respective distributing circuits 8 and 9. The inside or microphone programs are obtained by microphones 10, suitably placed in the various public rooms of the building and connected through conductors 11, control room panel 12, conductors 13, amplifier 14, and conductors 15 to a double-pole double-throw switch 16 or its equivalent. The provision of switch 16 permits the connection of the microphone circuit to either of the distributing circuits 8 or 9 whenever an inside program is offered in place of an outside program, the unused radio receiving set being cut out by the switch 5 or 6. Thus when two radio programs are desired the switches 5 and 6 are closed and the switch 16 opened. If, however, the program of radio receiving set 1 and a microphone program are desired, the switches 5 and 16 are closed and the switch 6 opened, the switch 16 being closed so as to connect the microphone circuit to the distribution circuit 9.

Preferably, some of the rooms are equipped with sound reproducers of the loud speaker type instead of the usual head set type. Inasmuch as head sets require a smaller intensity of current for their operation than is required by the loud speakers, the distribution circuits are divided or branched into head set circuits 17, 18 and loud speaker circuits 19, 20 and the intensity of the head set current decreased by adjustable step-down transformers or other suitable means 21 and 22. These head set and loud speaker circuits are connected to head set and loud speaker panels 23 and 24 respectively to complete the wiring of the system up to the communication channels leading from the control room.

The head set circuits 17 and 18 are connected through the panel 23 to the respective communication channels 25 and 26 and the loud speaker circuits 19 and 20 are connected through the panel 24 to the communication channels 27 and 28. These two sets of channels function as main feeders, connecting the control room circuits with a number of branch circuits 29 and 30 respectively, on each floor, the connection being made through junction boxes 31 containing a switch for each communication channel. Each branch circuit 29 and 30 is connected to a separate group of rooms, each room being provided with a double circuit receptacle 32 of any suitable type for such connection. The head sets are connected to branch circuits 29 and the loud speakers to branch circuits 30 through a double circuit cord and plug 32^a, a selector switch 33 and a cord 34. As used with the head set the selector switch 33 is mounted in a closed switch box 35 and is operated by a handle 33^a projecting beyond the box. The box 35 is mounted in the drawer 36 of a table

or somno 37, and in a position such that ample space is provided for the storage of the head set and cord 34 when not in use. In order to provide a clearance for the cord 34 and thus permit the drawer to be closed when the head set is being used, the front upper edge of the drawer is cut away, as at 38.

The loud speakers may be of any suitable type, a speaker of the drum type as shown in Figure 6 being preferred. As used with the loud speaker the selector switch is of the construction previously described, its parts being suitably built into the casing of the speaker and being controlled by a handle 33^b which is preferably fitted at the upper side of the speaker.

In the operation of the system, assuming that sound modulated current is being received from two different sources, the control room operator regulates the intensity of current in the distribution circuits 8 and 9 in any well known manner, the intensity being regulated to a point where satisfactory operation of the loud speakers is obtained. The desired intensity of current for the head sets is obtained by suitably adjusting the tapes of the step-down transformers 21 and 22 and it will thus be seen that the head set currents and loud speaker currents may be severally regulated to the intensity desired. With the communication channels thus properly energized, the occupant of any room may select the program he desires by operating the selector switch handle 33^a or 33^b as the case may be to one position wherein the switch connects the reproducing unit to circuit 8 or to the other position wherein the switch connects the reproducing unit to circuit 9. In this manner the occupant of a room is provided with a range of programs and with the means of selecting any of the programs offered.

While the above method of regulating the current intensity is preferred, it is readily apparent that other means of regulation may be used without departing from the scope of this invention. For instance, the current may be amplified for head set use and step-up transformers employed to increase the intensity of the loud speaker current.

Obviously, if desired, more than one microphone program may be substituted for the radio programs by being connected to the respective channels 8 and 9 and thus a selection of the two local programs may be made, the wiring connections for these purposes being sufficiently obvious from the foregoing to require no illustration.

Having fully described my invention, I claim:

1. A system for the reception and reproduction of sound modulated currents comprising a central station, at least two radio receiving sets in said station, an auxiliary station, a sound reproducing unit in said auxiliary station, at least two circuit channels ex-

- tending between the central and auxiliary stations, the circuits of which are adapted for connection to the respective receiving sets, additional sound modulated current sources adapted for connection in said central station to either of said circuit channels, and a selective switch in said auxiliary station for connecting the reproducing unit to either of said circuit channels. 5
2. A system for the reception and reproduction of sound modulated currents comprising a central station and a series of auxiliary stations, sound reproducing units of the head set type in certain of said auxiliary stations, sound reproducing units of the loud speaker type in the remaining auxiliary stations, at least two radio receivers in the central station, main circuit channels extending from said receivers, each main circuit channel 10 having a branch leading to the auxiliary stations equipped with reproducing units of the head set type and another branch leading to the auxiliary stations equipped with reproducing units of the loud speaker type, regulating means for creating a difference of current intensity between and appropriate to said head set and loud speaker branches, and a selective switch at each auxiliary station for connecting the reproducing unit thereof to either of said circuit channels. 15
3. A system for the reception and reproduction of sound modulated currents comprising a central station and a series of auxiliary stations, sound reproducing units of the head set type in certain of said auxiliary stations, sound reproducing units of the loud speaker type in the remaining auxiliary stations at least two radio receivers in the central station, at least two main circuit channels the 20 circuits of which are adapted for connection to the respective receiving sets, additional sound modulated current sources adapted for connection in said central station to either of said circuit channels, each circuit channel 25 having a branch leading to the auxiliary stations equipped with reproducing units of the head set type and another branch leading to the auxiliary stations equipped with reproducing units of the loud speaker type, regulating means for creating a difference of current intensity between and appropriate to said head set and loud speaker branches and a selective switch at each auxiliary switch for connecting the reproducing unit thereof to either of said circuit channels. 30
4. A system for the reception and reproduction of sound modulated currents comprising a central station and a series of auxiliary stations, sound reproducing units of the head set type in certain of said auxiliary stations, sound reproducing units of the loud speaker type in the remaining auxiliary stations, at least two radio receivers in the central station, main circuit channels extending 35 from said receivers, each main circuit chan-
- nel having a branch leading to the auxiliary stations equipped with reproducing units of the head set type and another branch leading to the auxiliary stations equipped with reproducing units of the loud speaker type, 70 means for decreasing and controlling the intensity of the current in said first-named branch and a selective switch at each auxiliary station for connecting the reproducing unit thereof to either of said circuit channels. 75
- In testimony whereof I hereby affix my signature.
